GEARING FOR ROTARY IRONS

Harry Schlesinger, Des Moines, Iowa

Application July 5, 1938, Serial No. 217,462

3 Claims. (Cl. 74—421)

One object of my invention is to provide a simple and inexpensive gearing mechanism for a laundry iron of the type such as shown in the Alfred F. Yoerg Patent No. 2,080,682 of May 18, 5 1937.

A further object is to provide step down gearing mechanism for transmitting rotation from a motor on a laundry iron housing to a sole plate at the bottom of the housing, the sole plate being 10 rotatable relative to the housing for increasing the surface travel of the sole plate over that secured by manual movement of the iron itself across the material being ironed.

Another object is to provide step down gearing mechanism which is so designed that it can be located in a gear casing which is made rotatable relative to a stationary part, such as a sleeve, the power shaft for the gear casing extending into the sleeve and novel connection being made between the power shaft and the gear casing, such 20 mechanism being entirely enclosed in the gear casing.

More particularly it is an object of my invention to provide step down gearing mechanism which can be used in connection with a rotary 25 sole plate of a laundry iron as disclosed, or can be applied to any other desired use where step down gearing mechanism enclosed within a gear casing is desirable.

A further object is to provide a stationary 30 sleeve with a gear casing rotatably mounted on it and gearing connections between a power shaft extending into the sleeve and the gear casing including an arm extending laterally from the sleeve and carrying a countershaft, there being 35 gear connections between the power shaft, the countershaft and the interior of the gear casing itself.

With the contemplated objects in view, as well 40 as others which will become apparent as my description proceeds, my invention consists in the construction, arrangement and combination of the various parts of my device, whereby the objects contemplated are attained, as hereinafter more fully set forth, pointed out in my claims, 45 and illustrated in the accompanying drawing, in which:

Figure 1 is a side elevation, partly in section on a vertical center plane, showing my gearing mechanism operatively connecting a motor and a rotary sole plate of a laundry iron; and

Figure 2 is a sectional view on the line 2—2 of Figure 1 illustrating the relation of parts of the gear mechanism.

On the accompanying drawing I have used the

reference numeral 10 to indicate a sole plate. The sole plate 10 has a heating element 12 therein to which current may be supplied in any suitable manner. A gear casing G is mounted on the sole plate 10 and this casing is enclosed by a housing H. The housing H is surmounted by the motor M provided for the purpose of rotating the sole plate 10.

The gear casing G includes a bottom wall 13 and a top wall 14. The housing H has a depending hub 15 at its center in which is mounted a sleeve 16. The sleeve 16 is fixed relative to the hub 15 by a key 17 and a lock nut 18. The sleeve 16 depends through a bore 19 in the top 14 of the gear casing G. The gear casing is journaled relative to the sleeve by bearings 20 and 21 which are preferably of ball or roller type. From the foregoing description it is obvious that the gear casing G and therefore the sole plate 10 are rotatably mounted with relation to the housing H.

Within the gear casing G an arm 22 is keyed as 20 by a key 23 to the sleeve 16. The right hand end of this arm is forked to provide a pair of arms indicated as 22a. The arms 22a carry bearings 24 which journal a countershaft 25.

The motor M is of the usual electric type having an armature 26 and a field core 27. The field coils are indicated at 28. The shaft of the motor is indicated at 29 and depends through a bearing 30 to a position within the sleeve 16. A motor extension shaft 31 is provided which has an enlarged and socket-like upper end 31a. The motor shaft 29 extends into the socket end 31a of the motor extension shaft and carries a cross key 32 extending through slots in both the motor shaft 29 and the socket end 31a. This key is pinned in the motor shaft by a pin 33. The motor extension shaft 31 is journaled in the sleeve 16 by bearings 34.

A drive pinion 35 is secured as by a key 36 to the motor extension shaft 31. The drive pinion 35 meshes with a countershaft gear 37 secured to the countershaft 25 as by a key 38. Also secured to the countershaft 25 by a key 39 is a countershaft pinion 40. A ring gear 41 is secured as by screws 42 to the top 14 of the gear casing 16. The countershaft pinion 41 meshes with the ring gear 41. Since the sleeve 16 and the arms 22a are stationary relative to the housing H, the countershaft 25 is journaled in stationary bearings. Accordingly rotation of the motor shaft 29 will cause rotation of the drive pinion 35 and in turn the countershaft gear 37 and the countershaft pinion 40. Rotation of the pinion 40 causes rotation of the ring gear 41 and thereby of the

gear casing G and the sole plate 10 at a reduced speed relative to the motor shaft 29.

My arrangement of gearing permits the mechanism to be compactly arranged within the gear casing G where it may be entirely enclosed and lubricated from a supply of oil 43 in the bottom of the gear casing. The oil will be carried by the operating parts to all the various bearings and gear teeth. Any oil that works up along the shafts 31 and 29 or the interior of the sleeve 16, in addition to any that might come from the motor M, will be caught by a cup-like extension 44 on the upper surface of the gear casing top 14. Any excess oil in this cup-like portion will drain through openings 45 in a spacer disk 46 to the sleeve 16 and through perforations 47 in the wall thereof to the interior of the sleeve and thus back to the reservoir supply in the gear casing G.

The sleeve 16 is slotted adjacent the right side thereof as indicated at 48 to permit entrance of the teeth of the counter-shaft gear 37 to meshing relation with the drive pinion 35. The entire gearing assembly can be placed in the gear casing before its top 14 is assembled in position and thereafter the sleeve 16 can be secured by the lock nut 18 in the hub 15 of the housing H. This makes a very convenient assembly and permits ready connection of the motor shaft 29 with the motor extension shaft 31 for transmitting power to the gearing mechanism for rotating the sole plate 10.

Some changes may be made in the construction and arrangement of the parts of my gearing mechanism without departing from the real spirit and purpose of my invention. I intend to cover by my claims such modified forms of structure and use of mechanical equivalents as may be reasonably included within their scope.

I claim as my invention:

40 1. In power transmission means, a housing having a motor therein, a gear casing rotatably mounted relative to the housing and an operative connection between said housing and said gear casing comprising a sleeve extending from 45 said housing and fixed against rotation relative thereto, said sleeve entering said casing and said

casing being rotatably mounted on said sleeve by bearings on the outside of said sleeve, an arm extending laterally from said sleeve, a counter-shaft journaled in said arm, a motor shaft entering said sleeve and having a drive pinion therein, 5 a countershaft gear on said countershaft meshing with said drive pinion, a countershaft pinion on said countershaft and a ring gear secured to said gear casing and meshing with said countershaft pinion, said sleeve having an opening in 10 the side thereof through which said countershaft gear extends to meshing relation with said drive pinion.

2. The combination of a housing, a sleeve depending from the housing, a gear case having a 15 top member with a centrally located annularly upstanding neck portion to prevent escape of lubricant from said gear case and an imperforate bowl-shaped bottom member; a bearing connection between said bottom member and the end 20 of said sleeve, a bearing connection between said top member and said sleeve, a lateral extension from said sleeve between said bearing connections, a countershaft mounted on said extension, a drive shaft in said sleeve, a gear connection between said drive shaft and said countershaft and a gear connection between said countershaft and said top member of said gear case. 25

3. A motor housing, a sleeve depending from 30 the housing and fixed against rotation relative thereto, a gear casing surrounding said sleeve, said casing having an imperforate bowl-shaped bottom member and a top member forming a closure therefor, said bottom member being journaled on the end of said sleeve, and said top member being journaled on said sleeve adjacent said housing, a motor shaft in said sleeve, a drive pinion on said motor shaft, a lateral extension from said sleeve intermediate said journals, 40 a stub shaft carried by said extension, a gear on said stub shaft meshing with said pinion, a gear fixed with reference to said casing, and a pinion on said stub shaft meshing with said fixed gear. 45

HARRY SCHLESINGER.
